UNITED STATES PATENT OFFICE.

ALFRED WILLIAM BEUTTELL, OF NEW YORK, N. Y.

ILLUMINATING DEVICE.

1,107,649.

Specification of Letters Patent. Patented Aug. 18, 1914.

Application filed April 17, 1908. Serial No. 427,667.

To all whom it may concern:

Be it known that I, ALFRED W. BEUTTELL, a subject of the King of Great Britain, and a resident of the borough of Manhattan of 5 the city of New York, in the county and State of New York, have invented certain new and useful Improvements in Illuminating Devices, of which the following is a specification, reference being had to the accompanying drawings, forming a part 10 hereof.

The invention relates more particularly to improvements in parabolic reflectors and to their use in connection with "double-ended" 15 incandescent lamps or lamps having substantially straight filaments, the general object being to provide an illuminating device in which the light developed may be under absolute control and may be most effectively 20 utilized or distributed.

The reflectors employed in accordance with the invention have a long and continuous reflecting surface which is substantially parabolic in cross section and the lamps are 25 mounted so as to extend along this surface in a straight line with their filaments substantially coincident with the focal line thereof.

In the employment of my improved 30 illuminating device for the purpose of lighting different objects such as pictures, book-cases, etc., it is possible to obtain uniform lighting effects which in most cases are much to be desired. For this purpose I preferably 35 place an illuminating device at one end of the picture, case or other article to be illuminated and make the side of the reflector which is nearest or closest thereto shorter than the other side. In this way, and by 40 placing the reflector at such an angle that its principal axis will cut the other end of the article to be illuminated, I so distribute the direct and reflected illumination that the direct illumination will be reinforced by the 45 reflected illumination at the points most requiring it, or in other words, as will be seen more particularly hereinafter upon reference to the drawing, I combine the direct and reflected rays to produce a uniform illumination. 50 In still other cases, it is desirable to concentrate the light from the illuminating device upon a particular object or space and yet to avoid any sharp definition between the illuminated portion of the object or space 55 and the non-illuminated portion adjacent

thereto, and for this purpose I modify the parabolic surface by bending the edges thereof inwardly to a slight extent and thereby causing some of the rays from the device to be slightly divergent and producing a diffusion of light around the central portion or nucleus whereby there is no sharp contrast between the illuminated and the non-illuminated portions of the article or space to be lighted.

In the drawings in which the improvements are illustrated, Figure 1 is a view in elevation of the illuminating device with one side of the reflector shorter than the other side. Fig. 2 is a view thereof in transverse section. Fig. 3 is a diagrammatic view showing the application of the improvements to the lighting of a picture or case.

Referring to Figs. 1 and 2, it will be seen that the reflector *a* consists of an elongated or extended trough-shaped device substantially parabolic in cross section and presenting a continuous reflecting surface. It may be constructed from any suitable material and in any suitable manner although for 80 most purposes it is preferable to construct the reflector from sheet metal and to bend the edges over as illustrated at *b* and *c* in order to form beads to receive the conducting wires of the external supply circuit. 85 The lamps *d* are of the double-ended variety each having a substantially straight filament *e* and being preferably of the well known "Linolite" construction. The ends of the lamp are received in supporting sockets *f* 90 the latter being provided with contact pieces *g* which are connected with the feed wires in the beads *b* and *c* in such a way that the contact pieces in adjacent sockets are electrically connected with opposite feed wires, 95 thus establishing a circulation through each lamp. When mounted in the sockets these lamps are arranged in a straight line within the reflector with their filaments extending along the focal line or axis of the reflector, 100 this line being the line connecting the foci of the parabolas formed by cutting the reflector transversely at any point.

It will be obvious that different conditions will determine the precise shape and 105 size of the reflector aside from its parabolic properties. In Fig. 3, for instance, where it is shown diagrammatically in relation to a picture to be illuminated, the side of the reflector which is nearest or closest to the 110

picture is made shorter than the other side. In this way the end of the picture nearest the illuminating device will receive the maximum illumination from the direct rays; 5 the intensity of such illumination of course varying inversely as the square of the distance from the lamp. It will be seen however that the main axis of the reflector cuts the picture near the other end thereof so 10 that the most intense portion of the reflected light will be directed upon said other end of the picture.

It was stated at the outset of this specification that the invention related particularly to the use of parabolic reflectors in connection with incandescent lamps having substantially straight filaments, and while most of the features of the invention have been developed with such a lamp in view, 20 many of the improvements are not inconsistent with the employment of a different kind of lamp and particularly a different kind of tubular lamp. The improvements are not limited therefore to employment in 25 connection with straight filament lamps, as in some cases it will be advantageous to employ the improved reflectors in connection with other forms of lamp. Many other changes, modifications and variations may 30 be made in the embodiment of the present

improvements without departing from the invention.

I claim as my invention:

1. The combination with an object to be illuminated, of an elongated reflector of 35 substantially parabolic form in cross section, one side of said reflector being located close to one edge of the surface to be illuminated and the principal axis of the reflector intersecting that portion of the surface to be illuminated which is remote from the reflector, and an incandescent lamp filament section in alinement with the focal axis of the reflector.

2. The combination of an object or surface to be illuminated and means for illuminating the same, which means is provided with an elongated reflector of substantially 45 parabolic form in cross section, one side of said reflector being located close to one edge 50 of the surface to be illuminated and the principal axis of the reflector intersecting that portion of the surface to be illuminated which is remote from the reflector.

This specification signed and witnessed 55 this 7th day of April A. D., 1908.

ALFRED WILLIAM BEUTELL.
